UNITED STATES PATENT OFFICE.

CHARLES A. KETTERER, OF EAST ST. LOUIS, ILLINOIS.

SIDE-ICING REFRIGERATOR.

1,369,443.

Specification of Letters Patent. Patented Feb. 22, 1921.

Application filed August 29, 1918. Serial No. 251,903.

To all whom it may concern:

Be it known that I, CHARLES A. KETTERER, a citizen of the United States, and resident of East St. Louis, in the county of St. Clair 5 and State of Illinois, have invented certain new and useful Improvements in Side-Icing Refrigerators, of which the following is a specification, containing full, clear, and exact description, reference being had to the 10 accompanying drawings, forming a part thereof.

My invention relates to improvements in side icing refrigerators and has for its object an ice container which may be slid out 15 of the side of the refrigerator so that ice may be placed in the same. A further object is to provide a refrigerator of a display or counter type with an ice receptacle which may be slid out from the side, for 20 the purpose of charging it with ice, thereby eliminating the top doors as is in common practice at the present time.

In the drawings—

Figure 1 is a front view of a portion of a 25 refrigerator showing my device located therein.

Fig. 2 is a cross sectional view of the chilling chamber of a refrigerator with my device in position.

Fig. 3 is a horizontal cross sectional view taken on the line 3—3 of Fig. 2, viewed in the direction of the arrow.

Fig. 4 is a vertical cross sectional view on the line 4—4 of Fig. 2.

Fig. 5 is a front view of a modified form of refrigerator.

Fig. 6 is a perspective view of the container used in my modified form and

Fig. 7 is a perspective view of the supporting leg made use of in my modified form.

In carrying out my invention, I provide a refrigerator 8 which is of the ordinary construction, having a chilling chamber 9 45 in which is located my improved ice receptacle 10. This receptacle comprises a front door 11, and a back 12. The door 11 is provided at its bottom with a pair of rollers 13, which run along the floor. Each 50 side of the door 11 is provided with a latch 14. This latch is of the ordinary construction, such as used on ice boxes, and is not shown in detail as its structure is well known to the art.

The front door 11 is also provided with a handle 15 for the purpose of drawing the

ice receptacle 10 from the refrigerator. The back 12 is provided with a pair of rollers 16 which ride on tracks 17 located in the bottom of the chilling chamber. The door 11 and the back 12 are connected together by supporting strips 18 and 19 and secured to the strips 18 is the ice container 20, which is provided at its bottom with a short pipe 21 to allow the water resulting from the melting ice to drip out. Beneath the container 20 and secured to the strips 19, I place an auxiliary drip pan 22, which catches the drippings from the container 20.

This drip pan 22 is provided with a pipe 70 23, which extends through the back 12. In the bottom of the refrigerator I mount a drip pan 24 which catches the drippings from the auxiliary pan 22 and from thence it is conducted through a pipe 25 which 75 leads to a suitable waste receptacle. Around both sides and the top of the back 12, I place a flange 26, which contacts with a depending flange 27 formed near the front end of the box, so that when the ice receptacle is drawn forward for charging, the flanges 26 and 27 contact closing the interior 80 of the ice box from the outer atmosphere and preventing the escape of cold air from the refrigerator.

The drip pipe 23 leading from the auxiliary drip pan 22 is so arranged that when the container 10 is drawn forward the drainage accumulating in the pan 22 will be directed into the pan 24 and at no time 90 will any of the drippings come outside of this pan and fall on the floor.

In the modified form I provide an ice container 30, which is provided on two of its sides with a T-iron 31. This T-iron fits 95 against or on top of a similar T-iron 32, which is secured to each side of the chilling chamber. On the front of the container 30 is placed a handle 33, the purpose of which is for drawing the container from the chilling chamber for charging it with ice. At each corner of the receptacle 30 I place angle irons 34, which support near their bottom ends a drip pan 35. This drip pan is provided with an opening 36 which will 100 allow the accumulating water to drip into the main drip pan located in the bottom of the refrigerator. On the front pair of legs I hingedly mount a pair of bars 37, the free 105 ends of these bars being connected together with a U-shaped bar 38. The bars 37 and the bar 38 forming a leg when the receptacle 110

30 is withdrawn from the refrigerator and by the peculiar construction of this supporting leg, the front end of the receptacle is kept from tilting, because if the receptacle 5 is drawn too far out the weight of the receptacle will cause these legs to straighten out and force the receptacle backward and bring the receptacle to its normal position. Furthermore, if the receptacle is not drawn 10 out far enough, the weight of the receptacle resting on these legs will have a tendency to pull it out. It is understood, of course, that when I use my modified form, the opening 36 in the auxiliary drip pan 35 is 15 closed with a stopper so as to prevent any drip water from coming on the floor.

What I claim is:

1. A refrigerator comprising a storage chamber, a chilling chamber adjacent thereto, an ice container slidably mounted within the chilling chamber, rollers for supporting the ice container, means for withdrawing the ice container from the chilling chamber, and means carried by the ice container for 25 closing the chilling chamber when the ice container has been withdrawn.

2. A refrigerator comprising a storage chamber, a chilling chamber, an ice container situated within the chilling chamber, rollers 30 for supporting the ice container for permitting its withdrawal from and insertion in the chilling chamber, and means carried by the front and back of the ice container for closing the chilling chamber when the 35 container is withdrawn or inserted.

3. A refrigerator comprising a storage chamber, a chilling chamber, a slidable ice container located within the chilling chamber, means for holding the ice container

within the chilling chamber, means for closing the refrigerator when the ice container is withdrawn therefrom, and rollers for supporting the ice container.

4. A refrigerator comprising a display chamber, a chilling chamber, an ice receptacle located in the chilling chamber, said ice receptacle comprising a front and a back, each composed of a solid sheet of material, a set of upper and lower strips connecting front and back parts of the ice 50 receptacle, an ice container mounted between the upper pair of strips, an auxiliary drip pan located between the lower pair of strips and beneath the ice container, rollers mounted on the front and back of the ice receptacle and tracks for the rollers which are mounted on the back of the ice receptacle.

5. A refrigerator comprising a display chamber, a chilling chamber, a slidable ice receptacle located within the chilling chamber, an ice container mounted in the ice receptacle, an auxiliary drip pan located beneath the ice receptacle, a main drip pan located in the bottom of the chilling chamber, a pair of rollers mounted at the rear of the 65 ice receptacle, a pair of tracks mounted in the main drip pan on which the rollers ride and a second pair of rollers mounted in front of the ice receptacle and adapted to ride upon a support for the refrigerator.

In testimony whereof, I have signed my name to this specification, in the presence of two subscribing witnesses.

CHARLES A. KETTERER.
